United States Patent Office.

CALVIN W. SHERWOOD, OF CHICAGO, ILLINOIS.

Letters Patent No. 75,588, dated March 17, 1868.

IMPROVEMENT IN PORTABLE BOOK-CLAMPS.

The Schedule referred to in these Letters Patent and making part of the same.

TO ALL WHOM IT MAY CONCERN:

Be it known that I, CALVIN W. SHERWOOD, of the city of Chicago, in the county of Cook, and State of Illinois, have invented certain new and useful improvements in devices for carrying books, &c., which I call a Book-Grapple; and I do hereby declare that the following is a full, clear, and exact description thereof, reference being had to the accompanying drawings, making a part of this specification, in which—

Figure 1 is a top view, the upper portion being carried to the side of the lower on the cords; and Figure 2 a side view.

Like letters refer to the same parts in both figures.

The nature and object of my invention consist in constructing a book-grapple or device for carrying school-books, &c., of a light and convenient frame, and locating the windlass at the end, so as to avoid cutting or weakening the upper cross-bar at its weakest point, and avoid the frequent breakage which occurs when the ratchet or windlass is at the centre, and in making the lower part a box, or providing it with a box for stationery, such as pens, rubber, pencils, &c., and such other things as are convenient in attending schools.

To enable others skilled in the art to make and use my improved grapple, I will proceed to describe its construction and operation.

The bars A and C are made of wood or other suitable material, about eleven inches in length and two in width, and of sufficient thickness to give the required strength. The handle D is attached to the bar C by sections of wire cut to a proper length, and riveted to the bar and handle. A small wire will be sufficient, as it is not desirable to cut or weaken this bar at or near the middle, for the reason that when a number of books are placed in it, a considerable pressure is required to hold them, which makes the bar liable to break. To avoid this difficulty, I attach the handle firmly, and place a small windlass at the end. This windlass will be most conveniently made by bending up the ends d of a piece of sheet brass, and passing the shaft F through them, as shown. At the end of the shaft I attach a flat (or other formed) bar, its ends projecting equally from the centre and turning close to the edge of the bar C. It is held in place by the slides a a, which are so placed as to hold the windlass at each quarter turn. These slides are fitted loosely, so that by tipping the grapple, they will slide forward and catch the winch, and by relieving them from pressure, they can be returned to place in the same manner; but to insure this operation, small points, b, are turned out at their rear ends, so that they can be operated with the hand. The cord E, which is permanently attached to the opposite end of the bar C, passes down through the bar A, and along through a groove in the bottom of said bar to the other end, where it passes through holes in both bars, and is then permanently attached to the shaft F of the windlass, upon which it is wound to secure the books, slates, &c., placed in it. To the bar A, I attach what I call a stationery-box, which is of the same width as the bar, about one inch deep and ten inches long; it may have a separate bottom, or the bottom can be formed by the bar A. I usually divide the box into compartments by partitions e, leaving one of them sufficiently long to receive pens and pencils. One compartment may be fitted to an inkstand or bottle, so that it can be carried with safety. The box is covered by a sliding lid, which, as will be seen, cannot get out of place when the grapple is in use, as the cord will prevent it from coming out if the pressure does not. This sliding lid may be made of a rule, as shown, which adds to its compactness and convenience.

The manner of using it and its operation will be apparent without description.

Having thus fully described my invention, what I claim as new, and desire to secure by Letters Patent, is—

1. A book-grapple, consisting of the bars A and C, with the cord E, and windlass F, with the stops a, all constructed and arranged to operate substantially as described.
2. In combination with a grapple for holding the books, I claim the box B, constructed and arranged for use, substantially as herein described.
